UNITED STATES PATENT OFFICE

146,201

DESIGN FOR A SET OF PLAYING CARDS

Ethel C. Van Wagner, Cheshire, Conn.

Application March 29, 1945, Serial No. 118,783

Term of patent 3½ years

(Cl. D34—13)

To all whom it may concern:

Be it known that I, Ethel C. Van Wagner, a citizen of the United States, residing in the town of Cheshire, county of New Haven, and State of Connecticut, have invented a new, original, and ornamental Design for Set of Playing Cards, of which the following is a specification, reference being had to the accompanying drawings, forming a part thereof.

Figs. 1 to 4 inclusive are plan views of different groups of the set of playing cards showing my new design.

The design on the back of the cards is conventional.

I claim:

The ornamental design for a set of playing cards, as shown and described.

ETHEL C. VAN WAGNER.
